EVI WILLSON CHRISTIE, OF SEWAREN, NEW JERSEY, ASSIGNOR TO WHEELER CONDENSER AND ENGINEERING COMPANY, OF CARTERET, NEW JERSEY, A CORPORATION OF NEW JERSEY.

CONDENSING APPARATUS.

1,135,661.

Specification of Letters Patent. Patented Apr. 13, 1915.

Application filed April 10, 1914. Serial No. 830,856.

To all whom it may concern:

Be it known that I, Evi Willson Christie, a citizen of the United States, residing at Sewaren, in the county of Middlesex and 5 State of New Jersey, have invented an Improvement in Condensing Apparatus, of which the following is a specification.

My present invention relates to condensing apparatus, and particularly to a surface 10 condensing apparatus, in which a hotwell is employed. In the use of the apparatus of this class, if, for any reason, the hotwell pump stops, or operates inefficiently, the condensate accumulates or backs up and is 15 liable to flood the air pump employed and thus injure the same and break down the vacuum in the condenser.

The object of my present invention is the provision of an apparatus in which this difficulty is overcome by employing devices for 20 automatically closing the passage between the condenser and the air pump suction when the condensate from the condenser accumulates to a certain extent, or backs up to 25 a predetermined height, so that the air pump cannot become flooded, and also one in which the pressure on both sides of the devices employed may be equalized, so that the parts may return to their normal positions 30 when the condensate has dropped below a predetermined level in order that the entire apparatus may operate during the continuous working of the system in which it is employed.

In carrying out my invention, in connection 35 with the shell of the condenser, which is provided with an outlet for the condensate, I employ a receptacle for this condensate, to which a hotwell pump is suitably connected. The condenser shell is also provided 40 with a nozzle or similar connection leading to the suction of an air pump, and this nozzle, or other connection, is divided into compartments, one of which leads directly 45 to the air pump and the other to the interior of the condenser. This nozzle is also provided with a float valve casing, in which there is a suitable float valve adapted to close a port in the partition wall in the 50 nozzle, the float valve casing being suitably connected to the receptacle for the condensate so that when the condensate rises to a predetermined point, it floats this valve and closes the said port, thereby shutting off

communication between the air pump and 55 the condenser. The nozzle is also preferably fitted with a suitable by-pass valve for equalizing the pressure on the opposite sides of the float valve, after the condensate has dropped below a predetermined level, in order 60 that the float valve may automatically return to its normal position, at the same time, as will be understood, placing the condenser in direct communication again with the air pump. Still furthermore, I may employ 65 a suitable means for indicating the fact that the float valve has operated to shut off communication between the air pump and the condenser, all of which will be herein-after more particularly described.

In the drawing, Figure 1 is an end elevation of a condenser illustrating the improvements comprising my present invention, and Fig. 2 is a partial cross section illustrating the same on a large scale.

Referring to the drawing, 10 indicates the condenser shell, provided with a series of condenser tubes 11, fixed at their respective ends in tube plates, which are suitably secured to the ends of the condenser, as is customary. In suitable positions the condenser shell is provided with an opening 12, for the discharge of the condensate or condensed steam. A boss preferably surrounds this opening 12, and to this boss a receptacle 13 is suitably connected. The condenser shell 10, in a suitable position, is also fitted with a nozzle 14, provided at its extremity with a flange 15, by which the same may be connected either directly or through a required 90 pipe to the suction end of an air pump. The nozzle 14 is preferably provided with a partition wall 16, dividing the same into compartments 17 and 18, the compartment 17 leading directly to the air pump, and the 95 compartment 18 to the interior of the condenser shell through a port 19 therein, and in the partition wall 16 there is a port 20, in which there is fitted a ring and a bearing hub 22, the ring in the bearing hub being 100 connected by a suitably spaced radial arm 23, or otherwise.

Made integral with, or suitably connected to the nozzle 14, and preferably depending therefrom, is a float valve case 24, in which 105 there is a float valve 25, which may be centered therein by suitable ribs 26, or otherwise. At its upper end, this float valve 25

is provided with a stem 27, which extends through and operates in the bearing hub 22. The float valve case 24 is connected to the receptacle 13 by means of a pipe 28 or 5 otherwise.

I may employ a suitable alarm for indicating the position of the float valve 25. As illustrated in the drawing, I have shown the nozzle 14 provided with a pair of contacts 29 and 30 fixed in the compartment 17 and electrically connected to terminals 31 and 32, suitably secured to the nozzle exteriorly thereof. These terminals may be connected through suitable wiring with an 10 annunciator or bell 33, and a battery 34, so that when the float valve rises sufficiently far to contact with the surface of the ring 21, the stem 27 engages the contacts 29 and 30, thereby closing the circuit to the annunciator and giving an audible alarm. It will be understood, however, that the alarm feature forms no material part of my invention, and that the one described herein, or any other suitable alarm, may be employed if so 15 desired. The partition wall 16 is also provided with a port 35, and I employ a by-pass valve 36, to which is connected a stem 37, a cap and gland 38, through which the stem passes, and a handle wheel 39 for operating the same, so that this by-pass valve may be seated against the valve seat provided therefor in the partition wall to close the port 35 or moved from its seat to open the same. I have also indicated the hotwell 20 pump by the reference numeral 40, and shown same connected to the receptacle 13 by means of a pipe 41, it being understood that the discharge end of the hotwell pump 40 leads to a suitable hotwell.

40 In the operation of the hereinbefore described apparatus, the parts during normal conditions are in the positions as indicated in the drawing. If, however, for any reason, the hotwell pump does not operate 45 satisfactorily, the condensate accumulates or backs up until it reaches a sufficient height to cause the float valve 25 to rise, and bear against a seat on the face of the ring 21, whereby communication between the air 50 pump and the interior of the condenser is shut off. In so doing, as hereinbefore stated, the float valve or stem may close an electric circuit in order to give an audible alarm that the hotwell pump is not operating 55 properly, and that the float valve has been actuated to shut off communication between the discharge and the air pump. This condition maintains until the hotwell pump has been given attention and made to operate 60 properly when, as will be understood, the condensate drops and the by-pass valve 36 may be opened to equalize the pressure in the compartments 17 and 18, whereby the float valve will drop to its normal or initial 65 position when the by-pass valve may be

closed again so that communication may be again restored between the condenser and the air pump. Furthermore, it will be understood, that the operation of this apparatus is possible during the continued working of the system in which the same is employed. 70

I claim as my invention.

1. In a condensing apparatus and in combination, a condenser having an opening 75 therein for the discharge of the condensate, a connection attached thereto and having two compartments therein, one adapted to be connected to an air pump and the other leading to the interior of the condenser, 80 there being provided a port in the wall separating the said compartments, a float valve in the compartment leading to the interior of the condenser, and a valve seat fixed in the said port in the wall between the 85 said compartments.

2. In a condensing apparatus and in combination, a condenser having an outlet for the condensate and a connection leading from the said outlet to a hotwell pump, a 90 connection secured to the body of the condenser and having two compartments therein, one adapted to be connected to an air pump and the other leading directly into the interior of the condenser with a port in the 95 wall dividing the one compartment from the other, a float valve in the compartment leading directly to the condenser, a valve seat fixed in the said port and against which, when raised, the said float valve bears, and 100 a pipe extending between the said compartment leading to the interior of the condenser and the said connection to the hotwell.

3. In a condensing apparatus and in combination, a condenser having an outlet for the condensate and a connection leading from the said outlet to the hotwell pump, a connection secured to the body of the condenser and having two compartments therein, one adapted to be connected to an air pump and the other leading directly into the interior of the condenser with a port in the wall dividing the one compartment from the other, a float valve in the compartment leading directly to the condenser, a valve seat fixed in the said port and against which, when raised, the said float valve bears, a pipe extending between the said compartment leading to the interior of the 110 condenser and the said connection to the hotwell, and means in the said wall dividing the said compartments and operative exteriorly of the said connection for equalizing the vacuum in the said compartments. 115

4. In a condensing apparatus and in combination, a condenser having an outlet for the condensate and a connection leading from the said outlet to the hotwell pump, a connection secured to the body of the con- 120

5 denser and having two compartments therein, one adapted to be connected to an air pump and the other leading directly into the interior of the condenser with a port in the wall dividing the one compartment from the other, a float valve in the compartment leading directly to the condenser, a valve seat fixed in the said port and against which, when raised, the said float valve bears, a 10 pipe extending between the said compartment leading to the interior of the condenser and the said connection to the hot-well, and means for operating an audible alarm when the float is in position against the 15 said valve seat.

5. In a condensing apparatus and in combination, a condenser having an outlet for the condensate and a connection leading from the said outlet to the hot-well pump, 20 a connection secured to the body of the condenser and having two compartments therein, one adapted to be connected to an air

pump and the other leading directly into the interior of the condenser with a port in the wall dividing the one compartment 25 from the other, a float valve in the compartment leading directly to the condenser, a valve seat fixed in the said port and against which, when raised, the said float valve bears, a pipe extending between the said compartment leading to the interior of the condenser and the said connection to the hot-well, means in the said wall dividing the 30 said compartments and operative exteriorly of the said connection for equalizing the 35 vacuum in the said compartments, and means for operating an audible alarm when the float is in position against the said valve seat.

Signed by me this 2nd day of April, 1914. 40
EVI WILLSON CHRISTIE.
